UNITED STATES PATENT OFFICE.

COURTLAND SKINNER, OF CHICAGO, ILLINOIS, ASSIGNOR TO FREDERICK C. AUSTIN, OF SAME PLACE.

APPARATUS FOR SEPARATING MATERIALS BY CENTRIFUGAL FORCE.

SPECIFICATION forming part of Letters Patent No. 617,865, dated January 17, 1899.

Application filed December 7, 1896. Serial No. 614,741. (No model.)

To all whom it may concern:

Be it known that I, COURTLAND SKINNER, a citizen of the United States, residing at Chicago, in the county of Cook and State of Illinois, have invented a certain new and useful Improvement in Apparatus for Separating Materials by Centrifugal Force, of which the following is a specification.

My invention relates in general to centrifugal apparatus adapted for treating pulverized or granular masses composed of substances having different degrees of specific gravity, so as to separate the heavier from the lighter ones, and it relates in particular to a variety of centrifugal apparatus in which the lighter particles of the outwardly-moving mass of material are stopped and carried back inwardly by an opposing fluid stream or current, while the heavier ones are allowed to continue their outward movement.

In an application for Letters Patent of the United States serially numbered 614,740, filed contemporaneously herewith, I have illustrated and described a novel and useful improvement in means for and method of treating materials in the above-mentioned manner.

The distinctive feature or characteristic feature of my said invention is that the fluid stream or current is forced directly in opposition to the outwardly-flying material by means operated and controlled independently of the means by which the material is subjected to centrifugal force—that is, the materials while moving outwardly through the passages of the rotary receptacle are opposed by an inflowing fluid current which is varied independently of and without varying the speed of the rotary receptacle; also, the arrangement permits a variation of the outward movement of the materials through said passages without varying the opposing fluid-pressure. By so doing I obtain certain novel and useful results particularly set forth in my said other application.

In carrying out my invention I can force either a liquid, such as water, or a gas, such as air, in opposition to the outwardly-projected material and to such end can employ means for supplying either a liquid or a gas under pressure. However, the apparatus which I have invented and which I desirably employ

in carrying out my invention is preferably somewhat modified when one or the other of such fluids is employed. Consequently I have set forth and claimed in my said other application both the broader features of my invention and the minor features which adapt it for utilizing a liquid as the opposing fluid and have filed the present application setting forth and claiming the features relating particularly to the use of a gas as the opposing fluid.

In the accompanying drawings, Figure 1 is a view illustrating an apparatus embodying my invention. Fig. 2 is an enlarged vertical section of the separator in which the separating process occurs, taken on a plane passing through the axis of rotation of its treatment-chamber; and Figs. 3 and 4 are horizontal sections taken on lines 3 3 and 4 4, respectively, in Fig. 2.

The material to be treated—such, for instance, as mineral-ore pulp—is desirably confined in a dry state in a suitable reservoir, such as the reservoir A, Fig. 1, which can be conveniently supported upon a standard A². From the reservoir A the material is fed to the rotary treatment-chamber provided by a rotary receptacle B², Fig. 2—as, for example, by way of a feed-pipe A', extending downward from the reservoir A through an opening in the top of the receptacle B² and into and nearly to the bottom or floor of the latter. The material thus delivered to the rotary treatment-chamber is projected outwardly in all directions from the axis of rotation of the receptacle B² in opposition to a gaseous stream or current which is forced into and inwardly within an exterior or surrounding gas-receiving chamber conveniently provided by a vertically-arranged inclosing shell or casing B'—as, for example, by way of a supply-pipe C', attached near the upper end of the latter, and thence into the rotary treatment-chamber provided by the rotary receptacle B² by way of suitable side openings with which the latter is provided. As a result the particles of the lighter substance are stopped at the side openings of the receptacle B² and carried back within the treatment-chamber which it provides and are carried out of such chamber by the current,

while the particles of the heavier substance continue their outward movement through the side openings in the rotary receptacle and into the chamber provided by the shell 5 or casing B' preparatory to their recovery.

The construction and arrangement of the rotary receptacle B², its inclosing shell or casing B', and adjuncts, which together comprise what I term the "separator," are in the main 10 similar to the preferred construction and arrangement of the corresponding members of the apparatus of my said other application, and hence will be described herein only briefly. Thus briefly described the rotary 15 receptacle comprises a flat disk-shaped top having an opening which receives the feed-pipe A', a similarly-shaped bottom, and an upwardly-flaring or conically-shaped body portion secured in position between the top 20 and bottom and arranged with the opening of its upper end in communication with the opening of the top. The conical body portion, however, in place of having longitudinal openings extending its entire length, as 25 in the apparatus of my said other application, is constructed with openings only at its upper end. In this way the dry material fed into the lower end of the receptacle providing 30 the treatment-chamber works upwardly, and so acquires a uniform momentum sufficient for separating purposes before coming 35 into opposition to the gaseous stream or current. The openings at the upper end of the conical body portion of the receptacle B² are desirably formed by longitudinally-extending 40 and inwardly-pointed slats b², which are arranged in circular form, with their outer edges in close proximity to one another, and which are respectively inclined transversely 45 from the radial. The rotary receptacle thus formed is conveniently mounted for rotation upon a vertically-arranged rotary driving-shaft E, which is attached to the lower end of the receptacle and is provided with a suitable pulley E'.

The upper end of the rotary receptacle B² is desirably constructed with a tubular cylindric extension B⁶, which serves as an outlet 50 for the gaseous stream or current and the lighter particles and also as a bearing or journal for the upper end of the receptacle.

As a simple arrangement for receiving and removing the gas and lighter particles arising from the treatment-chamber by way of the 55 tubular extension B⁶, an annular vessel B⁸, having an internal opening B⁸ and a spout B⁷, is arranged above the casing B' and around the upper end of the extension B⁶, so that the lower edge of its opening B⁸ registers with the upper edge of the latter. The casing B' is conveniently mounted upon a support or standard D and has its lower end provided 60 with a bearing e for the shaft E, which bearing is arranged in alignment with a bearing e' for the shaft E at the lower end of the standard D. The portion of the chamber provided by the casing B', surrounding or exterior to

the receptacle B², serves as a chamber for receiving the heavier particles preparatory to their recovery. As an arrangement for withdrawing or recovering such heavy particles I have shown a removable pan or drawer II, arranged between a horizontal shelf B⁹, having circumferential openings b⁹, and the bottom or floor of the shell or casing B'. The air or 70 other gas can be forced into the separator by any suitable means adapted for supplying a gas under pressure and capable of being regulated so as to vary such pressure. As one arrangement I have shown, Fig. 1, a rotary 75 fan or blower C, attached to the pipe C' and adapted to supply air under a pressure dependent upon its speed of rotation. In my said other application I have shown a method of obtaining the relation which must exist between the speed of rotation of the rotary receptacle and the pressure under which the fluid is supplied. Such method is likewise applicable to the apparatus herein described, it being observed, however, that in water and 80 in air a different ratio exists between equal falling sizes of substances having unequal degrees of specific gravity.

What I claim is—

1. A centrifugal separator comprising an 95 outer stationary inclosing shell or casing, providing an exterior chamber adapted for primarily receiving and containing air under pressure, and also for receiving the comparatively heavy particles of material after separation and preparatory to recovery; means for supplying air under pressure, and an internally-arranged rotary receptacle inclosed within said shell or casing and providing a centrifugal treatment-chamber having its upper end provided with an opening adapted to serve both as a material-inlet and an air-outlet; said rotary receptacle also having its side walls provided with openings adapted to serve both as inlets for the air and as outlets for the comparatively heavy particles of material, substantially as described.

2. In a separator in which the materials are separated by the coöperation of centrifugal force and an opposing current of air, a rotary 115 material-receiving chamber adapted to subject the materials to centrifugal force, and having upwardly flaring or divergent side walls; a feed-pipe arranged to deliver the materials to the said chamber at a point near the 120 latter's lower end or bottom; means for rotating the said chamber, and means for supplying air under pressure; the said rotary chamber being provided at its upper end with a series of side openings or passages wherein 125 the said materials and air will meet in opposition, the relatively heavy particles of matter being allowed to pass out, while the relatively light particles are carried back into the rotary chamber and, with the air, discharged from 130 the separator.

3. In a separator in which the materials are separated by the coöperation of centrifugal force and an opposing current of air under

pressure, a rotary receptacle having upwardly flaring or divergent side walls, and a series of outwardly-contracted and non-radial or tangential side openings arranged in and about its upperend; the said openings being adapted to afford passages wherein the said materials and air will meet in opposition, substantially as described.

4. In a separator in which the materials are separated by the coöperation of centrifugal force and an opposing current of air, a rotary material-receiving chamber adapted to subject the materials to centrifugal force, and having upwardly flaring or divergent side walls; the said rotary chamber being provided at its upper end with a series of side openings or passages wherein the said materials and air will meet in opposition; the relatively heavy particles of matter being allowed to pass out, while the relatively light particles are carried back into the rotary chamber, and with the air discharged from the separator; means for supplying air under pressure, and means for preventing rotation on the part of the air outside of the said rotary receptacle; 25 substantially as described.

5. In a separator in which the materials are separated by the coöperation of centrifugal force and an opposing current of air under pressure, a rotary receptacle having upwardly flaring or divergent side walls, the upper portions of said walls being composed of slats or the like, arranged to provide side openings or passages for the admission of air and wherein the said materials and air will meet in opposition; the said rotary receptacle being also provided with a top opening for discharging the air and lighter particles of matter, substantially as described. 30 35

COURTLAND SKINNER.
